UNITED STATES PATENT OFFICE.

ANDREW PETERSON, OF NEWARK, NEW JERSEY.

MACHINE FOR OZONIZING AIR.

1,239,515.

Specification of Letters Patent. Patented Sept. 11, 1917.

Application filed August 19, 1914. Serial No. 857,454.

To all whom it may concern:

Be it known that I, ANDREW PETERSON, a citizen of the United States, and a resident of Newark, county of Essex, and State of

5 New Jersey, have invented certain new and useful Improvements in Machines for Ozonizing Air, of which the following is a specification.

This invention relates to a machine for 10 ozonizing air and relates more particularly to the arrangement of the ozonizing apparatus in a casing, and relates also to the means of distributing the air that is passed through the ozonizing apparatus. As ozone 15 is manufactured for distribution in a room or similar closed compartment, it produces ozone which escapes directly from a machine in the proximity of people before it is properly mixed with the air, and since ozone 20 has a smell that is offensive to many, the ozonizing machines are not popular. Furthermore, ozone machines have a hum or noise which is unpleasant and very often makes the use of the machine prohibitive, 25 especially in institutions like hospitals where it has an effect on the patients by making them nervous.

In my improved form of ozonizing apparatus I provide a casing in which the ozonizing apparatus is installed, the casing having 30 an air inlet near the bottom and an air outlet near the top, and it also contains apparatus for forcing the air through the casing and through the ozonizing apparatus so that 35 the circulation of the air is not sluggish and the air is taken in at a point near the floor where it is less apt to be contaminated.

The invention is further designed to provide a casing in which partitions are placed 40 to cause the air to pursue a circuitous passage through the casing, and the structure is further designed to prevent noise, such as slight hums or vibrations, from being heard outside of the casing, whereby the device is 45 well adapted for use in hospitals and the like where quiet surroundings are desirable.

The invention is further designed to provide a dispensing or distributing structure that will thoroughly mix the ozone with the 50 air that comes through the machine and that has outlets to distribute the ozonized air at a material distance from the floor so that the deodorizing or purifying activity first takes place on the upper strata of the air in the 55 chamber or room, and as the work continues by reason of the circulation of the air, the

air will gradually work down to the level of the occupants and its strong odor is very much weakened and its presence is not unpleasant.

60 The distributing structure is preferably ornamental and can be made in the form of artificial plants, statuary, in fact any ornamental element that can be made to act as a distributing element, the ornamental structure being preferably mounted on the casing which acts as a pedestal for it, the ornamental structure having a passage through it which is in communication with the interior of the casing and thus acts to conduct the 70 ozonized air from the casing and provide outlets for its ejection. In the casing or plants the ozonized air can be projected from the trunk or other parts of the plant, and by being sent against and through the 75 leaves, is further mixed with the air and is in a sense broken up so that it is not offensive in smell, due to its being concentrated and not having been thoroughly mixed with the air.

80 The invention is illustrated in the accompanying drawing in which I show one embodiment of the invention, although it will be understood that ornamental structures and different arrangements of parts can be 85 made without departing from the invention.

In the drawing Figure 1 is a section of the casing, the ornamental structure however, which in the form shown is an artificial palm, being shown in elevation. Fig. 2 is a 90 section of the casing and the lower part of the ornamental structure taken on line 2-2 in Fig. 1. Fig. 3 is a section taken in the same plane, but illustrating the top portion of the ornamental structure showing the outlet openings and illustrating the manner in which the ozonized air is permitted to escape from the machine.

95 The invention comprises a casing 10 having sides and a back, the front 11 being 100 usually made in the form of a door to permit access to the inside of the casing and being preferably held in place by any suitable form of lock 12. The casing has a bottom 13 and a top 14, and a horizontal partition 15 is placed in the casing to divide it into an upper chamber and a lower chamber. In the lower chamber is mounted a suitable motor 16 which is driven by electric power, the connections and the wires, however, not being shown in the drawing, since 110 any form of wiring to bring about operative

results can be applied to this invention. The motor drives a blower 17 with an inlet 18 and an outlet 19. At the lower part of the casing are the inlet openings 20 which are placed in the lower part because the air is less apt to be foul in a room, the openings 20 preferably having sieves or screens 21 therein to prevent foreign objects or substances from being drawn into the openings 10 by the suction of the air.

Downwardly projecting partitions 22 and upwardly projecting partitions 23 terminate short of the bottom and top of the lower chamber, respectively, and thus cause the 15 air to take circuitous paths on each side of the motor and the blower, these partitions also acting to keep out any slight noise that may be in the motor while it is running.

Mounted in the upper chamber are the 20 ozonizers 24 which have their necks 25 projecting through the horizontal partitions 15 so that the open ends of the necks are adapted to receive the current of air that has come through the blower 17 and passes 25 through the outlet 19 of said blower. The ozonizers can be of any suitable form, but I prefer to use ozonizers of a type, one form of which is shown in Patent No. 974,789. If a transformer 25 is necessary, it can be 30 mounted above the ozonizers. The ozonizers are separated by a partition 26 which is divided to form the domes 27 and the downwardly projecting partitions 28 which terminate short of the partition 15. The upwardly projecting partitions 29 on each side of the ozonizers and the upwardly projecting partitions 30 outside the partitions 28 combine to cause the ozonized air, after it 35 has passed through the ozonizer, to pursue a circuitous route for the purpose of mixing the ozone well with the air, and the ozonized air finally passes underneath the downwardly projecting partitions 31 which project downwardly from the dome 32. The air 40 therefore passes up on the outside of the dome 32 and is directed by the plates 33 to the outlet opening 34 in the top 14. If desired I may provide a propeller or mixing wheel 35 which is freely rotatable in the 45 opening 34 and is rotated by the current of ozonized air passing from the casing, and its rotation serves to mix the air and the ozone thoroughly.

The partitions in the upper chamber 55 which give the air, which has been ozonized, a circuitous route toward the outlet of the casing also serve to prevent the escape of noise from the ozonizer if the ozonizer is of a type that causes any slight hum or buzzing in its operation.

Above the casing is the ornamental structure which acts to distribute the ozonized air, and the ornamental structure may be of any form and consists of statuary or artificial plants, in fact any device which would

be calculated to conceal its true function, the form illustrated being an artificial palm. The drawing shows a counterfeit flower pot 36 which has built up therefrom an ornamental trunk or stem 37, these elements surrounding an outlet pipe 38 which is connected with the outlet 34 of the casing and continues up through the plant, acting as a support for the stem 37. The top of the outlet pipe 38 is provided with leaves 39 which are disposed 70 in a natural manner at the top of the trunk or stem, and between the leaves and the stems of the leaves and also between the stems and the outer pipe 38 are outlet openings 40 which are so disposed that the ozonized air, having been mixed during its passage through the casing and also through the mixing wheel 35, is still further mixed with the air and passes out in an upper strata of air, where the heated and contaminated air 80 usually rises, and attacks all impurities, such as microbes and infected dust and destroys bacilla if such are present in the air.

This gradual feeding of the ozonized air to the air in a room or compartment has an 90 effect on the air to purify it without unpleasantly affecting the occupants of the room. Since the approach of the ozone to the occupants is gradual its offensive smell is not appreciable, and it furthermore is 95 ejected into the air where it will do the most good as it comes from the machine, at the same time being out of contact with the occupants of the room.

The partitions in the upper and lower 100 chambers, which partitions are shown as terminating short of the top and bottom walls or partitions, can be extended if desired, and then perforated on the extended portion to provide passage for the air and for the ozonized air, instead of permitting the air to pass over the top and bottom edges thereof, as 105 will be understood.

Having thus described my invention, I 110 claim:

1. In a machine for ozonizing air, a casing having a lower air inlet and an upper air outlet, a partition dividing the casing into an upper chamber and a lower chamber, a centrally arranged air propelling means in the lower chamber, a centrally arranged ozonizing apparatus receiving air from the lower chamber and delivering it in the upper chamber, successive partitions in both chambers, such partitions being adapted to surround the centrally arranged elements to cause a broken circuitous passage and mixing of the ozonized air and to prevent the noises incidental to the operation of said elements being clearly audible from the out- 115 side of the machine.

2. In a machine for ozonizing air, a casing having a lower air inlet and an upper air outlet, a partition dividing the casing into an upper chamber and a lower chamber, a 120

centrally arranged air propelling means in the lower chamber, a centrally arranged ozonizing apparatus receiving air from the lower chamber and delivering it in the upper chamber, successive partitions in both chambers, such partitions being adapted to surround the centrally arranged elements to cause a broken circuitous passage and mixing of the ozonized air and to prevent the noises incidental to the operation of said elements being clearly audible from the outside of the machine, and an air mixing wheel in

the outlet of the casing, a tube extending from the outlet, the mixing wheel being operated by the current of air passing through 15 it and acting with the tube to still further mix the ozonized air.

In testimony that I claim the foregoing, I have hereunto set my hand, this 12th day of August, 1914.

ANDREW PETERSON.
